UNITED STATES PATENT OFFICE

WILLIAM GRISWOLD HURLBERT, JR., OF WARREN, AND WILLIAM J. PURSER, OF YOUNGSTOWN, OHIO, ASSIGNEES TO THE BOSTWICK STEEL LATH COMPANY, OF NILES, OHIO, A CORPORATION OF OHIO

REENFORCED-METAL LATH

Application filed December 17, 1927. Serial No. 240,720.

This invention relates to the art of metal lathing, and more particularly to a reenforced type of non-expanded metal lath presenting a strong and efficient structure for use as a 5 supporting and reenforcing element for cementitious material in the construction of partitions, floors and ceilings and analogous building purposes.

A principal object of the invention is to 10 improve that type of metal lathing which has been extensively employed and known as the "truss loop" metal lath, whereby that particular type of lathing shall be given a maximum strength and stiffness, at the same 15 time providing effective keys for the plaster or other cementitious material. Also, it is an object of the invention to provide a novel lath formation having structural characteristics permitting the same to be manufactured 20 readily and economically.

Heretofore, it has been known that a desirable construction of metal lath can be made by slitting a metal sheet and deflecting to one side thereof portions of its metal, producing 25 an arched type of loops which by reason of their structural form contribute strength to the sheet and also which, by reason of their shape and extent of deflection from the flat plane of the sheet, provide keying openings 30 through which the plastic material will key or bond itself.

The present invention provides a material improvement in this type of lath construction chiefly by novel reenforcement and 35 strengthening thereof so it may become a substantial reenforcing factor in the wall or other structure. To that end the invention presents a structure which contributes most substantially and effectively to a reenforcement 40 of the sheet in practically every direction, not only lengthwise and cross-wise, but diagonally of the sheet by reason of the peculiarities of the reenforcement; also providing adequate and effective keying openings.

45 With these and other objects in view which will more readily appear to those familiar with the art the invention consists in the novel combination of features hereinafter more fully indicated and claimed, and the essential features of the new reenforced structure,

while susceptible of structural modification, without departing from the spirit and scope of the invention, certain preferred and practical embodiments thereof are shown in the accompanying drawings, in which:—

55 Figure 1 is a top plan view of a reenforced non-expanded metal lath fabricated in accordance with the present invention.

Figure 2 is a bottom plan view of a portion 60 of the new lath, exhibiting the bottom formation.

Figure 3 is a detail perspective view of the new lath, visualizing more particularly the structural characteristics of the reenforcement, in combination with the arched trussing 65 loops.

Figure 4 is a detail cross-sectional view of a portion of the product on the line 4—4 of Fig. 1.

Figure 5 is a similar view of a portion of 70 the product on the line 5—5 of Fig. 1.

Figure 6 is a plan view of a modification of the new structure.

Figure 7 is a detail sectional view of the modified structure on the line 7—7 of Fig. 6.

In carrying forward the invention any suitable machine or process may be utilized in the fabrication of the product, and it is not the intention to limit the invention by any particular machine or method of manufacture.

Accordingly, regardless of the steps of fabricating the new reenforced product the same involves in its general structure a flat metal body sheet 1 of steel or any suitable material for the purpose and of a suitable gauge. This body sheet is deformed during the process of fabricating the lath to provide the same with a plurality of longitudinally extending reenforcing ribs 2 of grooved formation, that is to say, the grooves in the sheet which form the ribs being open or exposed at one side of the sheet, while the closed sides of the grooves which form the ribs project from the opposite side of the sheet.

In connection with the longitudinally extending reenforcing ribs 2, a distinctive and important feature of the invention is the provision of the sheet with spaced transversely disposed reenforcing cross-ribs 3 arranged be-

tween every pair of the longitudinal ribs 2 and intercommunicating and connecting therewith. By intercommunicating is meant that the cross ribs 3 are also of the grooved type, and the grooves of said cross ribs 3 open directly into the grooves of the longitudinal ribs 2, as seen in Fig. 2, and the projecting parts of the said ribs 3 project from the same side of the sheet as the longitudinal ribs do, and integrally connect therewith, as seen in Fig. 1.

Thus, in the fabrication of the body sheet 1 in the manner described there is provided between every pair of the longitudinal ribs 2 a longitudinal succession or plurality of depressed plaster seats 4 bounded by connecting parts of the longitudinal and cross ribs 2 and 3. The metal in each of these depressed seats 4 is provided with parallel longitudinal 20 slits 5 which sufficiently release the metal between them to permit such metal to be upset or deflected from one side of the plane of the sheet into arched or bowed trussing loops 6. Each of these trussing loops, particularly 25 at its zenith or crown, has its opposite edge flanges 7 pinched inwardly into approximate parallel relation as best seen in Fig. 4 of the drawings, thus, giving additional and substantial reenforcement or stiffness to the loop 30 itself, as well as to the structure as a whole. Furthermore, the metal at the edges of the longitudinal slits 5 is bent in a direction away from the plane of the sheet to provide 35 deflected edge reenforcing flanges 8 which are also shown in Fig. 4 of the drawings.

It will now be seen that every depressed plaster seat 4 is surrounded by its reenforcing rib portions 2 and 3; also that the body metal is reenforced at the edges 8 of the slits 40 5, and is substantially reenforced throughout its length by the individually reinforced arched or bowed trussing loop 6. This reenforcement is multiplied throughout the entire 45 sheet lengthwise, between every pair of the longitudinal ribs 2 as well as crosswise of the sheet, (thus providing a structure of exceptional strength and stiffness, both longitudinally and laterally, which gives to the product high efficiency as a reenforcement for the wall 50 or other structure in which it is incorporated.

In addition to the utility of the features referred to, as reenforcing elements, for the lath product it will be seen that the structure provides most effective keys for the plastic 55 material by reason of the keying openings provided transversely beneath the arched or bowed trussing loops, and the keying openings provided through the sheet between the reenforced slotted portions 5. Also, the depression about each trussing loop, which constitutes a plaster seat 4, receives the plaster or other cementitious material in the form of a rectangular block that contributes materially to the substantial keying of the plaster to the 60 lath, in addition to the strength given to the

wall or other structure by the plaster bonding through the keying openings referred to.

By way of illustrating the range of modification that may be resorted to in carrying out the invention there is shown in Figs. 6 and 7 of the drawings a structural feature that adds an additional function to the cross ribs 3. That feature consists in piercing each cross rib 3 with a longitudinally disposed key opening 9 and striking outwardly the side edges of said opening producing edge flanges, as best seen in Fig. 7, which have the effect of reenforcement, and thereby maintaining the reenforcing effect of the cross rib. At the same time openings 9 are sufficiently 75 large to permit of the plaster or other cementitious material keying therein.

The drawings illustrate the trussing loops as well as the reenforcing cross ribs in staggered relation transversely of the sheet, but it will of course be understood that the invention is not limited to this particular arrangement, which is illustrated as a preferred example of the product.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

We claim:—

1. A non-expanded reenforced metal lath including a body sheet provided with offset arched loops projected from the plane of the sheet at one side thereof, and integral interconnecting longitudinal and transverse reenforcing ribs, each arched loop lying between and parallel to a pair of the longitudinal ribs and being confined between a pair of the transverse ribs.

2. A non-expanded lath including a body sheet having integral interconnected longitudinal and cross grooved ribs forming at one side of the sheet depressed plaster seats, and an arched grooved loop projected from one side of the plane of the sheet within each of said plaster seats.

3. A metal lath consisting of a sheet of metal provided with longitudinal and transverse stiffening ribs forming a plurality of separate plaster seats, and an arched rib pressed from the metal of the sheet within a plurality at least of said plaster seats.

4. A metal lath consisting of a sheet of metal provided with continuous longitudinal stiffening ribs providing parallel channels, transverse ribs across each channel dividing same into separate plaster seats, the transverse ribs of alternate channels being aligned with one another and disaligned with respect to the transverse ribs of the other channels, and a rib pressed from the metal of the sheet

within each of a plurality of said plaster seats.

5. A metal lath consisting of a sheet of metal provided with longitudinal and transverse stiffening ribs forming a plurality of separate plaster seats each of a length substantially twice greater than the width thereof, and a central longitudinally extending rib within each of a plurality of said plaster seats extending substantially throughout the length thereof.

6. In a metal lath, a sheet of metal provided with spaced slits, the metal between said slits being squeezed together and arched, and 15 the marginal portion of metal at the outside of the respective slits being bent to provide a flange disposed oppositely to the arched portion between the slits.

In testimony whereof we hereunto affix our 20 signatures.
